Primary Examiner — T Chase Nelson*Assistant Examiner* — Jonathan J. Han(74) *Attorney, Agent, or Firm* — NSIP Law(57) **CLAIM**

We claim the ornamental design for a wireless entrance security key, as shown and described.

DESCRIPTION

FIG. 1 is a front perspective view of a wireless entrance security key showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a rear perspective view thereof;

FIG. 9 is an enlarged side portion of the rear perspective view labeled "9" in the FIG. 8 view; and,

FIG. 10 is an enlarged portion of the side view labeled "10" in the FIG. 4 view.

The dot-dash broken lines in the drawings are used to indicate areas of enlargement and form no part of the claimed design. The short dash-dot broken lines shown in the drawings are included for the purpose of illustrating portions of the wireless entrance security key that form no part of the claimed design.
